ROLLING LAND BUCK

Percy Dixon, Klamath Falls, Oreg., assignor of
one-half to D. A. Kenyon, Klamath Falls,
Oreg.

Application April 12, 1938, Serial No. 201,628

2 Claims. (Cl. 37—179)

This invention relates to rolling land bucks, and has for its principal object to produce an improved device of this character for scraping and leveling land and making land checks, either border or contour, in preparation for the planting of cultivated fields, and for other like purposes.

A further object is to provide simple and efficient means for holding the body blade or board in different releasable latched positions whereby the blade or board may be securely held in scraping position and released for partial rotation and re-locked in different rotative positions for variably spreading and leveling the accumulated surface soil which has been crowded in front of the blade or board during the scraping action, and whereby also the latching means may be held in disengaged relation to the blade or board whereby the latter may be continuously rotated, at will, in the land checking operation.

A further object is to produce a simple and inexpensive structure in a device of this character, possessing the requisite strength and durability to withstand the rough usage to which it is subjected and which may be horse drawn or applied as an attachment to a tractor.

With these and other objects to be attained, as will later more fully appear, the invention consists in the general structure and in the particular parts and combinations and arrangements of parts thereof, as hereinafter described and pointed out in the appended claims, reference being had to the accompanying drawings illustrating a practical adaptation of the invention, and in which

Figure 1 is a top plan view of the device;

Figure 2 is a side elevation showing the blade element in normal scraping position;

Figure 3 is a fragmentary face view of the blade element;

eral 10, said element preferably comprising a wooden board of considerable heft for rigidity and durability. This board is surrounded marginally by a rectangular metal frame 11 at the opposite ends of which trunnions 12 are provided to which the rear end portions 13 of a yoke-like draft frame 14 are pivotally attached, said frame portions 13 having hubs 15 which are retained on the trunnions or spindle extensions 12 by collars 16 and cooperating cotterpins 17, as shown, or by any suitable approved retaining means. The forward portion of the draft frame 14 is convergent and attached to a suitable draft piece 18 having an apertured lug 19 at its outer end for the attachment of a coupling link 20. The draft frame is preferably reinforced by transverse braces 14' connecting the forwardly convergent side portions 14.

Secured on opposite sides of the board 10, near the ends thereof, are semi-circular roller shoes 21 having ears 22 at their opposite ends which are apertured for the reception of securing bolts 23 by which said members 21 are attached to the board 10, each pair of elements 21 being cooperatively applied in opposed relation to each other on the board whereby to constitute a roller on which the board may ride and rotate under certain conditions as will later more fully appear.

Detachably mounted at the middle of the blade element or board 10, and one on each side thereof near the opposite longitudinal margins thereof, is a diagonally opposed pair of sector-like frames 24 which are secured in place by bolts 25 whereby they may be firmly supported yet readily removable, at will. These brackets 24 have arcuate peripheral portions 26 which are substantially tangential to the longitudinal margins of the blade or board 10 and are provided at their outer ends with lugs 27 which project radially from the peripheral surface of the arcuate portion

lowered position of the lever 29 whereby to lock the blade or board 10 against rotation. Pivotedly mounted, as at 32, between the outer end portions of the longitudinal bars of the lever 29, is a tripping element having a cam portion 33 at one end and an oppositely extending angular arm 34 to which a tripping cord or link 35 is attached, said cord or link extending forwardly from the tripping device to a position on the tractor (not shown) within convenient reach of the operator. To prevent overtravel of the tripping element to its normal position, particularly when the lever member 29 is raised, a stop plate 33' is provided at the upper side of said lever 29.

15 In the normal position of the parts as shown in Figure 2, the lug 31 on the lever 29 is positioned in front of the upper frame portion 11 and said cam portion 33 of the tripping device rests on said frame portion 11, at which time the blade or board 10 is locked against rotation and rides on its lower longitudinal marginal portion with a scraping effect on the ground. Should it be desired to rotate the blade 10 partially and hold its lower marginal portion elevated above the ground, the cord 35 is pulled to rock the tripping element and press its cam portion 33 upon the adjacent frame portion 11, thereby raising the lever 29 until the lug 31 is moved clear of the frame member 11 (see Figure 4) whereupon the blade 10 is free to rotate and rides forwardly on the circumferential portion 26 of the lower bracket 24 and if the cord 35 is immediately released the lug 31 will ride upon the portion 26 of the upper bracket 24 and into the path of the lug 27 on said upper bracket, and upon engagement of said lug 27 on the bracket 24 with the lug 31 on the lever 29 further rotation of the blade 10 is prevented and said blade is then dragged on the lug portion 27 of the lower bracket 24 with the lower edge of the blade above the ground (see Figure 5). In this position of the blade 10 the loose soil which has been previously scraped up and accumulated in front of the board is levelled out beneath the blade to the depth corresponding to the elevation of the blade and thereafter the lever 29 is released from the upper bracket 24 and the board 10 is again rotated until a half turn is completed and the lower frame portion 11 has come in contact with the lug 31, whereupon the parts will again be in the position as shown in Figure 2. It will thus have been seen that the board 10 is releasably held in either the vertical normal position as shown in Figure 2 or in the partially rotated position as shown in Figure 5, or alternately released for rotation between these positions.

In this connection, it is noted that during the full half or complete rotation of the board 10 it is supported intermediate of said brackets 24 by the semi-circular shoes 21. In some cases, particularly when the apparatus is used for land checking, the frames 24 are removed so that the board is supported in its rotative movement entirely by the semi-circular members 21, the board 10 being held in its vertical position by the engagement of the lug 31 on the lever 29 with the upper frame member 11 and upon the release of said lug 31 from said frame member 11 the board will normally be rotated a full half revolution before being again arrested by the lug 31, provided, of course, the lever 29 has been lowered with the lug 31 in the path of said frame member 11, but if said lever 29 has not been so lowered the rotation of the board 10 continues on uninterruptedly. However, supplemental locking means is

provided to stop the rotative movement of the board before the completion of a half revolution, as shown in Figure 6. For this purpose locking dogs 36 are provided at opposite sides of the draft frame 14, said dogs 36, as shown, being of bell-crank form and pivotally mounted, as at 37, to swing in a horizontal plane into and out of the orbit of the longitudinal frame portion 11 on said blade element 10. For manipulating these dogs 36 and holding them in their locking and unlock- 10 15 20 25 30 35 40 45 50 55 60 65 70 75 80 85 90 95 100 105 110 115 120 125 130 135 140 145 150 155 160 165 170 175 180 provided to stop the rotative movement of the board before the completion of a half revolution, as shown in Figure 6. For this purpose locking dogs 36 are provided at opposite sides of the draft frame 14, said dogs 36, as shown, being of bell-crank form and pivotally mounted, as at 37, to swing in a horizontal plane into and out of the orbit of the longitudinal frame portion 11 on said blade element 10. For manipulating these dogs 36 and holding them in their locking and unlock- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 46

adjacent longitudinal edge of the board and having a circumferential lug, a locking lever on said draft frame having a stop lug engageable alternately with the upper marginal frame portion of said board and the circumferential lug on said bracket members, whereby to releasably lock the board in vertical and partially rotated position, a tripping element engageable with the marginal

frame of said board and with said bracket members for actuating said locking lever to retract its stop lug, and supplemental latch means on said draft frame for engaging the marginal frame of said board to releasably lock the board in partially rotated position. 5

PERCY DIXON.
